PER

United States Patent Office.

JAMES THOMAS, OF PARRYVILLE, PENNSYLVANIA.

Letters Patent No. 103,391, dated May 24, 1870.

IMPROVEMENT IN APPARATUS FOR OPENING AND CLOSING THE TOPS OF BLAST-FURNACES.

The Schedule referred to in these Letters Patent and making part of the same.

To all whom it may concern:

Be it known that I, JAMES THOMAS, of Parryville, in the county of Carbon and State of Pennsylvania, have invented a new and useful Improvement in Blast-Furnaces; and I do hereby declare that the following is a full, clear, and exact description thereof, which will enable others skilled in the art to make and use the same, reference being had to the accompanying drawings forming part of this specification.

Figure 1 is a vertical longitudinal section illustrating my invention.

Figure 2 is a detail view of the upper part of the cylinder with its attached pipes and wings.

Similar letters of reference indicate corresponding parts.

My invention has for its object to furnish an apparatus for automatically raising and lowering the bell that closes the top of the furnace and distributes the stock, automatically, so that it will be raised to close the furnace when the pressure of the blast is on, and be lowered when the pressure of the blast is off, thus guarding against danger from explosion, when the blast is off the furnace; and

It consists in the construction and combination of the various parts of the apparatus, as hereinafter more fully described.

A represents the hopper of the furnace.

B is the bell with which the furnace is closed when the blast is on the furnace, and which should be lowered when the blast is off the furnace, to prevent danger from explosions.

When the furnace is being charged the bell B is lowered, and serves to distribute the stock evenly about the furnace.

To the apex of the bell B is pivoted the lower end of the rod C, the upper end of which is pivoted to the end of the lever D. The lever D is pivoted to the standard or post E, and to its other end is pivoted the upper end of the connecting-rod F, the lower end of which is pivoted to the crosshead G, the ends of which move up and down on the ways H, and to which is attached the upper end of the piston-rod I, which passes down through a stuffing-box, and to the lower end of which is attached the piston J, which works up and down through the cylinder K, and the movement of which raises and lowers the bell B.

In the lower end of the cylinder K is formed a small hole K', through which the air in the lower part of

the cylinder K may pass in and out freely, as the piston J moves up and down.

With the upper end of the cylinder K is connected the lower end of the pipe L, with the upper end of which is connected a pipe M and three way-cock O. When the blast is used to operate the piston J this is all that is necessary. When the blast is used for operating the piston J, the pipe M should be connected with the blast-pipe between the furnace stop-valve and the furnace, so that when the blast is on the furnace, the pressure of the air may hold the piston J down and the bell B up, and when the blast is shut off, the weight of the bell B may cause it to drop, raising the piston J. When steam or water is used the said three-way cock must be connected with the device for operating the furnace-valve in such a way that the operation of closing the said valve to shut off the blast will adjust the said cock to open the connection between the cylinder-pipe L and the discharge-pipe N, to allow the steam or water to escape or be forced from said cylinder K by the weight of the bell B, and when the furnace-valve is opened to apply the blast, communication will be opened between the ingress or feed-pipe M and cylinder K, to admit the steam or water to force down the piston J and raise the bell B.

Having thus described my invention,

I claim as new and desire to secure by Letters Patent—

1. The combination of the hopper A, bell B, connecting-rod C, lever D, connecting-rod F, cross-head G, ways H, piston-rod I, piston J, cylinder K, and pipes, or pipe L M, with each other to enable the bell B to be raised and lowered automatically, by the operation of applying the blast to, or shutting it off from the furnace, substantially as herein shown and described.

2. The combination of the hopper A, bell B, connecting-rod C, lever D, connecting-rod F, cross-head G, ways H, piston-rod I, piston J, cylinder K, pipes L M N, three-way cock O, with each other, substantially as herein shown and described, to enable the bell B to be raised and lowered automatically by the operations of applying the blast to and shutting it off from the furnace.
